UNITED STATES PATENT OFFICE.

OTTO HUFELAND, OF MOUNT VERNON, ASSIGNOR TO J. C. STEPHENS, OF NEW YORK, N. Y.

MECHANICAL MOVEMENT.

SPECIFICATION forming part of Letters Patent No. 339,987, dated April 13, 1886.

Application filed January 15, 1886. Serial No. 188,687. (No model.)

To all whom it may concern:

Be it known that I, OTTO HUFELAND, a citizen of the United States, residing at Mount Vernon, in the county of Westchester and State of New York, have invented new and useful Improvements in Mechanical Movements, of which the following is a specification.

This invention has for its main object to provide novel and efficient mechanism for moving a sewing-machine shuttle in a rectilinear shuttle-race, but the invention is applicable for other purposes.

This invention consists in the combination, with a lever and its fulcrum-pin, of a movable support for the fulcrum-pin, guides for the support, constructed to retain said pivot in a rectilinear path, an oscillating arm, a pivotal connection between this arm and the lever, a revolving shaft, and suitable connections between the arm and the shaft; so that by imparting to the arm an oscillating motion within the proper limits the free end of the lever is caused to move in a straight line. With the lever and the oscillating arm is further combined a carriage pivoted to the end of the lever and a connecting-rod pivoted at one end to the carriage and at its opposite end to the oscillating arm, so that the position of the carriage during its motion is governed by the oscillating arm and the lever.

In the accompanying drawings, Figure 1 represents a front view. Fig. 2 is a side view.

Similar letters indicate corresponding parts.

In the drawings, the letter A designates a lever, which has its fulcrum on a pivot, a. In the example shown in the drawings this pivot is secured to a slide, b, which moves in rectilinear guides c c; but other well-known means may be substituted for retaining the pivot a in a rectilinear path.

B is an arm, which is connected to the lever A by a pivot, d, and which is mounted on one end of a rock-shaft, e, to the opposite end of which is secured an arm, C, the end of which 45 engages with a lever, D. This lever has its fulcrum on a stud, f, and it carries a roller-stud, g, which engages with a cam, E, mounted on a shaft, F, to which a revolving motion is imparted by any means suitable for the purpose. It is obvious, however, that the connections between the shaft F and the oscillat-

ing arm B can be modified, as will readily suggest itself to any skilled mechanic. By revolving the shaft F an oscillating motion is imparted to the arm B within fixed limits, 55 and the free end of the lever A is moved in a straight line. If the oscillating arm should be moved beyond said fixed limits, the free end of the lever A would depart from a straight line.

G is a carriage, which is connected to the free end of the lever A by a pivot, g, and this carriage connects by a rod, H, with the oscillating arm B, one end of said rod being attached to the carriage by a pivot, i, and to 60 the arm B by a pivot, h. The position of the carriage in relation to the lever A and its movement depends upon the distance of the pivot i from a line, j k, drawn through the pivot g at right angles to the lever A and upon 65 the distance of the pivot h from the pivot d. If those two distances are alike, the carriage will move in a rectilinear path, and will be held in a position parallel to its original position throughout the entire movement of the 70 lever A, as indicated in dotted lines in Fig. 1. In this figure the bottom line of the carriage is parallel to the path in which it moves; but said bottom line may be at an angle to said path. If the distance between the pivot i and 75 the line j k is greater or less than the distance between the pivot h and the pivot d, the carriage will oscillate on its pivot g during the motion of the lever A from one end of its stroke to the other.

In the example shown in the drawings, an additional connection, H', is shown between the carriage and the oscillating arm B. This additional connection, however, is only required if both connections H and H' are made 80 of a flexible material, such as cord.

What I claim as new, and desire to secure by Letters Patent, is—

1. The combination, with the lever A and its fulcrum-pin a, of a movable support for 95 the fulcrum-pin, guides for this support, constructed to compel said support to move in a straight line, an oscillating arm, a pivotal connection between this arm and the lever A, a revolving shaft, and suitable connections between 100 said arm and the shaft, substantially as shown and described.

2. The combination, with the lever A and its fulcrum-pin a , of a movable support for the fulcrum-pin, guides for this support constructed to compel said support to move in a straight line, an oscillating arm, a pivotal connection between this arm and the lever A, a revolving shaft, a cam, E, mounted on said shaft, and suitable connections between said cam and the oscillating arm, substantially as shown and described.

3. The combination, with the lever A and its fulcrum-pin a , of a movable support for the fulcrum-pin, an oscillating arm, a pivotal connection between this arm and the lever A, a carriage pivoted to the lever A, and a connecting-rod pivoted at one end to the carriage and at the opposite end to the oscillating arm, substantially as shown and described.

4. The combination, with the lever A and its fulcrum-pin a , of a movable support for the fulcrum pin, guides for this support constructed to compel said support to move in a straight line, an oscillating arm, a pivotal connection between this arm and the lever A, a carriage pivoted to the lever A, and a connecting-rod pivoted at one end to the carriage and at the opposite end to the oscillating arm, substantially as shown and described.

In testimony whereof I have hereunto set my hand and seal in the presence of two subscribing witnesses.

OTTO HUFELAND. [L. S.]
